UNITED STATES PATENT OFFICE.

GEORGE FOSTER REZNOR, OF MERCER, PENNSYLVANIA.

GAS BURNER.

Application filed March 15, 1923. Serial No. 625,209.

To all whom it may concern:

Be it known that I, GEORGE FOSTER REZNOR, a citizen of the United States, residing at Mercer, in the county of Mercer and State 5 of Pennsylvania, have invented new and useful Improvements in Gas Burners, of which the following is a specification.

My invention relates to gas-burners and the object thereof is to provide such burners with agitatable grids or screens for preventing back-firing from the burner-tips into the mixers. I place between the burner-tips and the mixer a grid or screen through which all the gas must pass on its way to 10 the burner-tips, and provide means whereby the grid or screen may be reversed or turned over so that any impurities which have lodged therein may be readily driven by the gas through the burner-tips but in the 15 reverse direction from that by which the impurities entered the same. The grid or screen may be jarred when reversed or turned in order to loosen the impurities so that the outgoing gas will more easily dislodge the impurities and carry them through 20 the burner-tips.

Referring to the accompanying drawing, Fig. 1 is a side view of a burner equipped with my invention, a portion being broken 30 away; Fig. 2, an end elevation of Fig. 1 complete; Fig. 3, a cross section of Fig. 1 on the line III—III; Fig. 4, a plan view of Fig. 1 with the cover member removed.

On the drawing, 1 designates the manifold 35 chamber of a multiple-tip gas-burner, and 2, the mixing chamber which receives air and gas at one end and delivers them mixed to the chamber 1 in a manner well known. The member 1 has the cover member 3 which 40 is provided on its upper side with a series of burner-tips or openings 4.

At or near the lower side of the cover member 3 is the axially-rotatable shaft 5 centrally arranged below the burner-tips 45 and mounted in the ends of the chamber 1. To the shaft is secured in any suitable manner a screen, which I have shown comprising a strip of fine-mesh wire netting 6 held in a frame of sheet-metal provided with 50 openings 7. The frame has its longitudinal center in the plane of the axial center of the shaft 5. The shaft and screen rotate or oscillate in the longitudinal opening or passage 8 connecting the interior of the cover member 3 with that portion of the chamber 1 which is below the screen. The edges of

the screen substantially fit the sides and ends of the opening 8, no matter which side of the screen is up; at least, the sides and ends of the screen and the opening are so close together when the sides of the screen are at right angles to the direction of travel of the gas therethrough, as to prevent the passage of enough gas to cause back-firing.

In order to ensure that the screen will 60 always lie squarely across the opening 8, as shown in full and dotted lines in Fig. 3, I provide the shaft with the crank or arm 9 adapted to engage the stop or block 10. The block is arranged so that the shaft 5 70 lies across the center of the face of the same with the arm 9 adapted to rest on the said face when the screen is seated in the opening 8 as shown in the drawing.

A lever 11 is pivoted on the pin 12 below the shaft 5 and has its lower end pivoted to the operating rod 13. The upper end of the lever has a longitudinal slot 14 in which the crank pin 15 on the outer end of the arm 9 is 80 slideable as the lever is operated by the rod 13. A 85 contractile spring 16 is connected to the pins 12 and 15. The spring not only seats the arm 9 on the block 10, but it ensures the throw of the shaft 5 in either direction as soon as the pin 15 has passed the dead center position with respect to the shaft 5 and the pin 12. The screen can be jarred by hand to loosen the dirt therein, or it can be jarred by releasing the arm 9 as soon as it passes the dead center or at any other line, the 90 spring causing the arm to engage the stop with sufficient force to loosen the dirt in the screen.

The word screen is to be taken in the broad sense of including grid and perforated sheet-metal, that is, devices having elongated or round gas passages.

I claim—

1. A gas burner, a mixer therefor, a screen between the two positioned to cause the gas 100 to pass through the same to the burner, and means for agitating the screen to dislodge matter trapped thereby.

2. A gas burner, a mixer therefor, and a screen arranged across an opening between 105 the burner and the mixer to prevent back-firing, and reversible to facilitate the dislodgement of matter trapped by the screen.

3. A gas burner, a mixer therefor, a screen movable to two positions, at each of which 110 the gas passes from the mixer through the screen to the burner, and means ensuring

that the screen shall return to one of the positions when moved from one position and then released.

4. A gas burner, a mixer therefor, a screen movable to two positions, at each of which the gas passes from the mixer through the screen to the burner, and means causing the screen to move to a second of said positions after it has been moved a predetermined distance from its starting position.

5. A gas burner, a mixer therefor, a screen movable to two positions, at each of which the gas passes from the mixer to the burner, a rotatable shaft supporting the screen, an arm carried by the shaft, and a stop ar-

ranged to be engaged by the arm when the screen is in either position.

6. A gas burner, a mixer therefor, a screen movable to two positions, at each of which the gas passes from the mixer through the screen to the burner, a rotatable shaft supporting the screen, an arm carried by the shaft, a stop arranged to be engaged by the arm when the screen is in either position, and a spring for moving the screen to one position after it has been moved from either position and then released.

In testimony whereof I hereunto affix my signature this 10th day of March, 1923.

GEORGE FOSTER REZNOR.
